UNITED STATES PATENT OFFICE.

ALBERT W. PHELPS, OF FRESNO, CALIFORNIA.

VENTILATOR.

1,265,509.

Specification of Letters Patent.

Patented May 7, 1918.

Application filed February 19, 1917. Serial No. 149,433.

To all whom it may concern:

Be it known that I, ALBERT W. PHELPS, a citizen of the United States, residing at Fresno, in the county of Fresno and State 5 of California, have invented a new and useful Ventilator, of which the following is a specification.

This invention relates to ventilators and is especially useful in connection with cars 10 intended to carry perishable goods, as, for instance, fruits, vegetables and the like.

An object of the invention is to cause circulation of the air in the car so as to insure uniform temperature throughout the car.

15 Another object is to properly ventilate all parts of the car while at the same time circulating the air.

Another object is to cool the air thus circulated.

20 Another object is to produce a system of this character of maximum effectiveness and simplicity of construction and operation.

Other objects and advantages will appear in the subjoined detail description.

25 The accompanying drawings illustrate the invention.

Figure 1 is a vertical mid section of a railway car embodying the invention.

Fig. 2 is a plan view, the car body being 30 in section on line indicated by x^2-x^2 , Fig. 1.

Fig. 3 is an enlarged plan section of the pump in Figs. 1 and 2, portions of the air tubes also being shown in section.

Fig. 4 is an enlarged fragmental vertical 35 section on line indicated by x^4-x^4 , Fig. 2.

Fig. 5 is a vertical section on line indicated by x^5-x^5 , Fig. 4.

Three things are accomplished by this invention, namely, the circulation of air from 40 top to bottom and from bottom to top of a car; admission of fresh air to and expulsion of heated air from the car to ventilate the car; and cooling of the air as it is being circulated.

45 The roof, floor, side walls and end walls of a railway car are indicated at 1, 2, 3 and 4 respectively, there being partitions 5 spaced from the end walls to form air cooling chambers 6, and there being a false floor

50 7 provided with air outlets 8 and spaced from the floor 2 to provide an air passage 9 between the floor and false floor. The air passage 9 communicates through ports 10 with the cooling chambers 6. In the drawings ice 11 is shown in the chambers 6 as the cooling agent for said chambers, but it

is understood that the cooling may be effected by other mediums or agents than ice, if desired. The ice 11 is spaced apart from the end walls 4 by suitable open spacing 60 frames or members 12 so that there will be air passages 13 from the upper portions of the chambers 6 to the ports 10 when the ice is in place.

Located in suitable position and, in the 65 instance shown in the drawings, about centrally of the car and in the upper portion thereof just beneath the roof 1 is a suitable air-circulating pump indicated in general by the character 14, and radiating from said 70 pump are circulation tubes 15, 15', intake tube 16 and exhaust tube 17; the circulation tubes 15, 15' extending in the instance shown in the drawings, longitudinally along the vertical mid plane of the car, and the intake 75 tube 16 preferably but not necessarily extending aslant toward one side wall 3 of the car and projecting therethrough and the outer end portion of said intake tube 16 being bent parallel with said side wall, and 80 the exhaust tube 17 extending aslant toward the opposite side wall of the car and projecting through said opposite side wall. The tubes 15, 15', and 17 are preferably but not necessarily gradually reduced in diameter 85 from their inner toward their outer ends and the tube 16 is gradually expanded from its inner toward its outer end so as to accelerate the flow of air to the discharge ends of said tubes. 90

The intake tube 16 is connected by an enlarged nipple 18 to the pump 14 and communicates with chambers 19, 20 and 21 of said pump, there being valves 22, 23 and 24 to control the passage of air through the 95 inlet ports 25, 26, 27 of said chambers from the nipple 18 and each of said valves being manipulated by a suitable handle 28 which may be conveniently reached from the interior of the car or elsewhere as desired. 100

The chambers 19, 20, 21 are provided with exhaust ports in the form of outwardly reduced nozzles 29, 30 and 31 respectively and said chambers are gradually reduced in cross sectional area from their middle portions toward their intake and exhaust ports. 105

The nozzles 29, 30 and 31 project into the enlarged inner ends of the tubes 15, 17 and 15' respectively and the outer ends of said nozzles are of less outside diameter than the 110 inside diameter of the tubes so that there will be annular suction ports 32, for the re-

spective tubes for the passage of air from the interior of the car into said tubes.

The tubes 15, 15' communicate at their outer ends with transversely extending tubes 33 respectively arranged in the upper portions of the cooling chambers 6, and said tubes 33 are provided with discharge orifices 34 at intervals therealong, said discharge orifices opening outward into the spaces beneath downwardly and outwardly curved 10 defectors or shields 35 that may be of any desired shape and that in the drawings extend transversely from side to side of the cooling chambers. The shields 35 may be 15 corrugated as shown to form a series of downwardly and outwardly directed channels 36 as clearly shown in Fig. 5.

No attempt is made to show and describe in detail the construction of the tubes 33 and 20 shields 35 since such construction is within the skill of those versed in the tube and sheet metal working arts and in the drawings they are shown of integral construction though they may be made separate if desired or for convenience in manufacturing.

The shields 35 and tubes 33 may be supported by the outer ends of the tubes 15, 15' respectively and the outer ends of said tubes 15, 15' may be supported by the partitions 30 5, or any other suitable supporting means may be provided for the tubes 15, 15', 33 and shields 35.

The pump 14 may be supported from the roof of the car by suitable brackets 37 and 35 the inner ends of the tubes 15, 15' and 17 may be supported from the roof of the car by suitable brackets 38.

In practice the method of ventilating and 40 cooling the car will be carried out as follows: The chambers 6 will be cooled by placing therein ice 11 or by any other suitable means and the car will be propelled by any suitable power in a manner well understood in the transportation art.

Assuming that the car is traveling in the direction of the arrow a , Fig. 2, air will naturally flow into the intake end of the tube 16 and from thence into the pump chambers 19, 20 and 21. The velocity of the air entering said chambers will be reduced somewhat at the middle portions of said chambers but will be again accelerated at the nozzles 29, 30 and 31 so as to create considerable suction at the suction ports 32 by 50 reason of the injection effect of the nozzles, thus drawing into the tubes 15, 15' and 17 air from the higher air levels in the car; and since the warmer air seeks the higher levels said warmer air will be drawn off through the agency of the pump 14.

The foregoing operation takes place when all of the valves 22, 23, 24 are open, and said valves will thus be maintained at certain degrees of opening according to the external 60 atmospheric conditions to be met with and

the character of the cargo being transported.

With the valves thus open it is clear that some fresh air will continually pass into the pump to be mixed with the air sucked 70 out of the upper portion of the car. Air from the chambers 19, 21 will pass together with air sucked through the ports 32 through the tubes 15, 15' and will be discharged through the ports 34 along the inner edges of the shields 35 and will be distributed by said ports and shields transversely from side to side of the chambers 6 downward over the ice 11. The air thus forced into the chamber 6 will pass downward between the cakes of ice and through the passages 13 and will be cooled and will pass through the ports 10 into the passage 9 and thence will be distributed by ports 8 from end to end of the car. The air thus 80 cooled in the cooling chambers 6, and discharged through the ports 8, as it becomes heated, either by the higher heat of the cargo or walls of the car or both, will rise in a manner well understood and subsequently will be withdrawn again and cooled as before.

From the foregoing it is clear that there is thus set up a circulation of air within the car and that the air circulates from the upper portion of the car through the cooling chambers and thence to the lower portion of the car. It is also clear that the air thus circulated in part is fresh external air drawn from the exterior of the car so as to afford 100 ventilation to the cargo space. In practice the valves 22, 23 and 24 may be so adjusted that the combined volumes of air flowing from the nozzle 30 and through the port 32 surrounding said nozzle is about 105 equal to the volume of air injected into the pump by the tube 16 so that the perfect circulation of air in the car will be effected.

When the external atmosphere is somewhat near the temperature of that desired 110 for the interior of the car, the valves 22, 24 may be partly closed so as to conserve the supply of cooling medium in the cooling chambers 6. When the external temperature is comparatively high the valves 115 22, 24 may be opened to their full extent so as to produce maximum circulation of air through the cooling chambers 6 and thus maintain the interior of the car at comparatively low temperatures.

From the foregoing described construction it is readily comprehended that circulation of the air is maintained in the car by motion of the car and that the air is cooled while it circulates, or that circulation of the 125 air may be maintained when the car is stationary if the pump 14 be of any well-known form of mechanically operated pump.

The intake tube 16 may be formed in sections as shown in Fig. 2 so that the outer 130

section 39 can be reversed at the joint 40 when the car is traveling in a direction opposite to that indicated by the arrow *a*.

The exhaust tube 17 may be provided with 5 a flap or other valve 41 which is opened outward by pressure of the outgoing air but which will be closed by the spring 42 when air is not being pumped from the car.

The partitions 5 may be provided near 10 their lower ends with ports 43 to allow some of the air from the cooling chambers 6 to pass directly into the cargo chamber. It is readily understood that when the ports 43 are provided the ports 10 and false floor 15 7 can be dispensed with and that when the ports 10 and false floor are provided the ports 43 may be dispensed with.

I claim:

1. The combination with a car, of a pump 20 having separate chambers, nozzles for the chambers respectively, a tube having its intake end surrounding one of the nozzles and spaced therefrom, the discharge end of said tube opening into the car, a second tube 25 having its intake end surrounding the other nozzle and spaced therefrom, the discharge end of said second tube extending outside of the car, and a third tube having its discharge end communicating with the 30 chambers, said third tube having its intake end projecting outside of the car.

2. The combination with a car, of a pump having separate chambers, nozzles for the chambers respectively, a tube having its 35 intake end surrounding one of the nozzles and spaced therefrom, the discharge end of said tube opening into the car, a second tube having its intake end surrounding the other nozzle and spaced therefrom, the discharge 40 end of said second tube extending outside of the car, a third tube having its discharge end communicating with the

chambers, said third tube having its intake end projecting outside of the car, and valves to control the flow of air from the third 45 tube to the chambers respectively.

3. The combination with a car, of a pump having separate chambers, nozzles for the chambers respectively, tubes having their intake ends surrounding the nozzles of some 50 of the chambers and spaced therefrom, the discharge ends of said tubes opening into different portions of the car, another tube having its intake end surrounding the nozzle of another of the chambers and spaced 55 therefrom, the discharge end of the last named tube extending outside of the car, and still another tube having its discharge end communicating with the chambers, the last named tube having its intake end projecting outside of the car.

4. The combination with a car, of a pump having separate chambers, nozzles for the chambers respectively, tubes having their intake ends surrounding the nozzles of some 60 of the chambers and spaced therefrom, the discharge ends of said tubes opening into different portions of the car, another tube having its intake end surrounding the nozzle of another of the chambers and spaced 65 therefrom, the discharge end of the last named tube extending outside of the car, still another tube having its discharge end communicating with the chambers, the last named tube having its intake end projecting 70 outside of the car, and valves to control the flow of air from the last named tube to the chambers respectively.

Signed at Los Angeles, California this 12th day of February 1917.

ALBERT W. PHELPS.
